ELECTRIC SAFETY WATER LIGHT

Augustus J. Le Strange, Jackson Heights, and
John D. Gibson, Pelham, N. Y.

Application April 20, 1943, Serial No. 483,718

6 Claims. (Cl. 9—8.3)

This invention relates to a self-contained electric light, primarily intended for use by those sailing the high seas, who may perchance find themselves compelled to abandon ship or otherwise find themselves in the water, said light serving to direct aid to the distressed person. However, the light may be used under conditions under which an ordinary flashlight may be used, and hence the light is not presumed to be restricted to such sea or distress use.

In view of the primary purpose, it is an important object of our invention to provide a self-contained unit which is water-tight and resistant to corrosion by sea water.

Another important object is to provide a unit which, when it strikes the water, will be self-righting and buoyant, the said unit being designed to float in a substantially upright position.

Still another object of this invention is to provide a device of the character described which, when not in use, remains unlit, but which when it strikes the water and assumes a substantially upright position, will automatically light up, and will continue lighted up for a substantial period of time or until the electrical cells or battery run down.

A further object of the present invention is to provide a housing for electric cells provided with shock-absorber elements, so as to cushion the internal assembly from the shock or impact when the unit strikes the water and thus prevent any injury to the battery or cells, or to the other electrical elements and connections, which might cause failure of the unit to light.

Another important object is to provide a device of the character described, which is inexpensive and reliable in its operation.

A specific object of the present invention is to provide an arrangement whereby the cells may be side-loaded and the said cells securely confined in place until purposefully expelled by the fingers of the hand, in a manner more particularly disclosed anon.

In furtherance of the immediately preceding objective, it is an important object of the present invention to provide a housing for said cells having suitable openings therein, said housing being preferably tubular and flexible diametrically.

While the above are some of the more important objects and features of the present invention, others will be disclosed as the description of the annexed sheet of drawing proceeds.

Referring to said drawing:

Fig. 1 is a vertical elevation, partly in sec-

tion, of a preferred embodiment of our invention, showing its external appearance and part of the internal structure.

Fig. 2 is a vertical elevation, partly in section, showing the internal assembly of elements and electrical connections. In this view the unit is right-side-up, and is the position it assumes when in the water to emit light.

Fig. 3 is an enlarged sectional view on the line 3—3 of Fig. 2, showing some additional detail and parts.

Fig. 4 is intended mainly as diagrammatic, to illustrate the manner in which a cell is forcibly passed into the tubular housing therefor. It is also diagrammatic of what happens when the cell is ejected. The view may be regarded as a horizontal sectional view at any convenient point along the tubular housing.

Fig. 5 is a sectional view on the line 5—5 of Fig. 2, and shows the normal position of the cell within the tubular housing.

Fig. 6 is a circuit diagram of the device.

Fig. 7 is an enlarged fragmentary sectional view of the lower end of the casing as shown in Fig. 2, but showing some additional detail and parts.

Referring to the said drawing, it will be observed that our unit or device comprises an outer casing 1, closed at one end, and open at the other to permit the insertion therein of the inner assembly, above alluded to and to be presently more specifically described. The said casing is made out of material which is both a non-conductor and which is resistant to corrosion, particularly by sea water. It may comprise a tubular member 1a and a closure member or plug 1b which is securely attached to said tubular member 1a by pins 1c, which are driven through said latter members, as clearly illustrated in Fig. 7. The tubular member 1a is screw-threaded at 2, around its outer surface for an appreciable distance below the open end in order to receive a lens closure 3, provided with an internally-threaded circular flange 3a. Between the hemispherical portion of the lens and the flange 3a is a flat annular portion 3b, between the surface of which and the rim 1d of the tubular member 1a, and the disc-shaped member 4, is tightly clamped a rubber gasket 5 which closes or covers the gap between said tubular member and said member 4, and thereby prevents leakage of water past said gap into the tube. The gasket 5 also, in a measure, forms a seal to prevent water from passing by the threads 2 and into the lamp chamber 6.

Referring now more particularly to the internal

assembly, it will be seen that the same comprises a preferably plastic and transparent tubular housing 7, the lower end of which is attached, by means of screws 8, to the member 9, the latter being preferably of heavy metal and a conductor. The said housing 7 has a plurality of superposed openings therein, numbered respectively 10, 11 and 12, which, for the sake of convenience, are arranged in vertical alignment. Seated upon the uppermost surface of the base member 9 is a metal coiled spring 13, such as is conventionally used in flashlights. Said spring has imposed thereon two standard flashlight cells 14a and 14b, in the usual superimposition for series connection. Said cells 14a and 14b are inserted into the tubular housing 7 through the opening 10 therein. It will be observed that the diameter of the cells exceed the width of said opening, but it is possible to force the said cells through said opening because of the inherent diametrical flexibility of the tubular housing, the forcing of said cells through said opening spreading the sides of the housing adjacent the opening to increase the apparent width of said opening to permit the cells to pass. This last-explained action and effect is clearly illustrated in Fig. 4. When the widest part of the cell passes the side edges of the opening, the deflected portions return to assume their normal curvature.

With respect to cell 14a, it will drop down the housing and come to rest on the spring 13. In inserting cell 14b, it is essential to push cell 14a down (against the resistance of spring 13), since cell 14a obstructs a considerable part of the opening 10 and it would not be possible to get 14b into the tubular housing because the height of the cell is such that its top would reach considerably above the upper edge of the opening 10 were cell 14b to be superimposed on cell 14a without depressing the latter.

It is possible, however, to depress cell 14a sufficiently to permit cell 14b to be inserted through opening 10 in the same manner as was done with respect to cell 14a. However, when cell 14a is released and permitted to return to normal position, it also lifts superimposed cell 14b to a position where the top part of the latter is engaged all around by the housing 7, with the exception of an opening 15, to the rear and in part above the front opening 10. Opening 15, however, is substantially smaller and is made sufficiently large though to permit the intrusion therethrough of the thumb (in whole or in part) or some other finger of the hand. This rear opening 15 is provided to facilitate the removal or ejection of the cell or cells from the housing 7 when occasion requires.

It will be observed that the center post of cell 14b comes in contact with a copper bus or strip conductor 16 which passes through a slot (not shown) in said housing 7 and is attached by means of screw 17 to an insulator disc 18 through an opening in said housing 7.

The said disc 18 acts to confine the cells 14a and 14b between it and spring 13 or base 9, whichever is preferred, and the area between said elements may be regarded as a cell compartment.

Supported on said disc 18 is a metal coiled spring 19, similar to spring 13, upon which is supported cells 14c and 14d, which are inserted into housing 7 through opening 11 in the same manner as that described in connection with the insertion of cells 14a and 14b. At the rear of cell 14d is an opening 20 having the same func-

tion with respect to the ejection or removal of cells 14c and 14d that opening 15 has with respect to the removal or ejection of cells 14a and 14b.

The center post of cell 14d contacts a loop 16a of the conductor 16 which passes through a slot (not shown) in the housing 7, the emerging end 16b of said conductor being attached by means of screw 21 to insulator disc 22, passing through a hole in said housing.

The loop 16a is clamped between the center post of cell 14d and disc 22, and the space between discs 18 and 22 may be regarded as another cell compartment.

The emerging end 16b of conductor 16 is connected by soldering, metal clip, or otherwise to one end of a cotton-covered flexible conductor wire 23, the other end being connected to one of the electrodes or terminals 24 (Fig. 6) of a mercury switch 25, which latter is attached by a suitable bracket, such as 26, to housing 7. Access to said mercury switch is made possible by the opening 12 in said housing member 7.

Connected to the other electrode 27 is one end of a cotton-covered flexible conductor wire 28, whose other end is connected to a suitable contact element designed and arranged to be contacted by the central terminal of lamp 29.

Fig. 2 shows a single such contact element 30. Fig. 3 shows the conductor 28 connected to a lug 31, which is slotted, or may be perforated, to permit the passage therethrough of screw 32. This lug is overlapped (or may overlap) by a part of a separate contact element 33 for the center terminal of the lamp. The overlapping portion of contact element 33 is also slotted, 33a, so that screw 32 may pass through both elements 31 and 33 and secure them both to the disc 4a, which latter is made of some preferably highly dielectric material.

Returning to the bottom of Fig. 2, and to the left side, it will be seen that there is another copper bus or strip conductor 34 running up the side of the housing. The lower end of said conductor 34 is attached by means of screw 8 to basal element 9 (which, as already stated, is preferably of heavy metal and a good conductor of electricity) through a hole (not shown) provided for that purpose in the housing 7. This same screw, as already mentioned, also acts to attach the lower end of housing 7 to said member 9. The said conductor 34 is attached to disc 18 by screw 35 passing through a hole (not shown) in housing 7.

The said conductor 34 is looped, 34a, said loop passing through a slot (not shown) in housing 7, and makes contact with coiled spring 19. The said conductor enters and emerges through the same slot, and the conductor continues, where it is attached to disc 22 by means of screw 36 passing through a hole in housing 7. The upper terminal portion of conductor 34 passes through a notch or slot 37 (Fig. 3) into the tube, and, as illustrated in Fig. 2, can be arranged to make direct contact with the spirally grooved ferrule 38 adapted to receive the lamp 29, and thereby completing the circuit.

In Fig. 3 there is shown a slightly different arrangement for making electrical connection between conductor 34 and ferrule 38. Here the inner end of conductor 34 is provided with a hole through which is adapted to pass screw 40. Said inner end of conductor 34, however, overlaps (or may overlap) a lug 41 which has a large perforation (not shown) adapted to annularly embrace and contact ferrule 38, while the oppo-

site end has a hole through which said screw 40 may pass through, the latter serving to attach both conductor 34 and lug 41 to disc 4a.

In order to allow for clearance between lug 41 and contact member 33, the disc 4a is provided with a depression or groove 42, so that normally the aforesaid two elements will be kept normally apart and thereby obviating a short circuit. However, as a matter of practice it is a good idea to insert an insulating washer 43 between the 10 two elements to make assurance doubly sure.

Should it be desirable to remove the cells for replacement purposes or otherwise, the housing 7 is removed from casing 1. The housing is grasped in the hand; thumb and index fingers are placed respectively (the one or the other) in the opening 10 and 15 (or 11 and 20, as the case may be). That means that the upper of the two cells, in the given compartment, will be engaged between said two digits. The upper cell is pushed down with both fingers and the finger in the opening 15 or 20, as the case may be, is pressed forward against the cell. The lower cell can be removed by turning the housing 7 upside-down, which would bring the said cell in position to be grasped between thumb and finger, front and rear.

Fig. 4 shows two arrows, one pointing toward the larger opening, the other toward the smaller opening. When inserting a cell you push it in the direction of the arrow pointing to the larger opening; when removing, you push the cell in the direction of the arrow pointing to the smaller opening.

It is recommended that where the lights forming the subject matter of the instant invention, are made part of the equipment of a vessel, that they be attached upside-down to a bracket having spring clips for holding said light so that it may be quickly detached. They may be connected by a chain or other means to life-preservers or similar equipment.

It will be apparent that the cells are connected in series-parallel, with the switch in series with the lamp. Fig. 6 shows the circuit diagram, and requires no explanation.

It will be observed that there is a large empty space in the compartment between disc 22 and disc 4 or lamp assembly unit. This space is required to keep the unit sufficiently buoyant so that it will project above the water sufficiently so that the light may be visible from a reasonable distance. It is also obvious that without this "buoyancy chamber" the unit would sink.

Attention is directed to the bowing of the several conductor strips 16 and 34 which impinge at spaced points along the unit against the inner walls of the casing 1a. This constitutes the shock-absorbing means alluded to above.

By proper adjustment, arrangement and design of the mercury switch, it is possible to have the light act as a blinker light. As the mercury switch at present used, and from which the annexed drawing has been made, is designed to give light through a swing of approximately 180° from the vertical, blinker action is not likely to occur unless the light is tilted by the waves or by the person, to a substantially horizontal position. The mercury switch obviously can be so constructed that a blinker effect will occur within a swing, say, of 90° from the perpendicular, less or more.

Having described our invention, what we claim is:

1. A self-contained light unit comprising a 75

water-tight casing, an inner removable housing, current-supply means therein, said casing having an air-space above said means sufficient to enable said unit to float in water, a lamp in circuit with said current supply means, a switch in said circuit normally open when said unit is inverted and adapted to close automatically when said unit is righted, and spring cushioning means disposed between the inner wall of said casing and the outer wall of said removable housing.

2. A self-contained light unit comprising an elongated water-tight casing, an inner removable housing, a lamp circuit including current-supply means confined to one end of the housing with the lamp at the other, there being an air-space between said current-supply means and said lamp sufficient to enable the casing to float in a substantially upright position with part of the unit submerged, a switch in said lamp circuit open when said unit is held in an upside-down position and adapted to automatically close when said unit is righted, and cushioning means disposed between the inner wall of said casing and the outer wall of said removable housing.

3. A self-contained light unit comprising an elongated water-tight casing, an inner removable housing, a lamp circuit including current supply means confined to one end of said housing with the lamp at the other, there being an air-space between said current-supply means and said lamp sufficient to enable the casing to float in a substantially upright position with part of the unit submerged, a mercury switch in said circuit, said switch being disposed in said air-space, with the electrodes at one end, and arranged in such a way that when the unit is upside-down, the electrodes will be at the top, with the mercury globule in the bottom of the containing vessel, whereas when the unit is righted the electrodes will be at the bottom with mercury covering the electrodes to close the switch, and cushioning means disposed between the inner wall of said casing and the outer wall of said removable housing.

4. A self-contained light unit comprising an elongated outer casing, an inner tubular housing having openings therein for the side-loading and removal of cells, means dividing said housing into cell compartments, cells in said compartments, a lamp, a switch, and conductors connecting said cells into circuit with said lamp and switch.

5. A self-contained light unit comprising an elongated outer casing, an inner tubular housing having openings therein for the side-loading and removal of cells, means dividing said housing into cell compartments and an air chamber, cells in said cell compartments, a lamp, a switch, and conductors connecting said cells into circuit with said lamp and switch.

6. A self-contained light unit comprising an elongated outer casing, an inner tubular housing of plastic material having openings therein for the side-loading and removal of cells, means dividing said housing into cell compartments and an air chamber, cells in said cell compartments, a lamp, a switch, and conductors connecting said cells into circuit with said lamp and switch, certain of said conductors being in the form of long bowed strips interposed between the inner wall of the casing and the outer wall of the housing so as to cushion the inner assembly against shock.

AUGUSTUS J. LE STRANGE.
